(57) **ABSTRACT**

A *chrysanthemum* plant named 'Zanmumajes' characterized
by its small sized blooms with red-purple ray florets and
prolific branching; natural season flowering date October 2
(week 40); blooming for a period of five weeks.

3 Drawing Sheets

1

Botanical designation: *Chrysanthemum x morifolium*
Ramat.

Cultivar denomination: 'Zanmumajes Red'.

RELATED CULTIVARS

The new plant is a flower color mutant of 'Zanmumajes'
(U.S. Plant Pat. No. 26,847)

BACKGROUND OF THE INVENTION

The present invention relates to a new and distinct cultivar
of *chrysanthemum* plant, botanically known as *Chrysanthemum x morifolium* Ramat., commercially known as a garden
mum, and hereinafter referred to by the cultivar denomina-
tion 'Zanmumajes Red'. 'Zanmumajes Red' is a product of
a breeding and selection program which had the objective of
finding flower color mutants from existing parent plants. The
new plant comprises a whole plant mutant of the parent
chrysanthemum named 'Zanmumajes' (U.S. Plant Pat. No.
26,847). A comparison between the parent and 'Zanmumajes
Red' is provided in the section description of the invention.

In order to obtain flower color mutants, unrooted cuttings
of the parent plant were irradiated in April 2013 at Zieken-
huis, Rotterdam, the Netherlands, with gamma radiation at
a dose of 15 Gy. These treated cuttings were then planted in
a controlled environment (greenhouse) in Rijsenhout, the
Netherlands. In this population of planted cuttings, the new
cultivar was discovered as a flower color mutant in October
2013 by Sjoukje Heimovaara in a controlled environment
(greenhouse) in Rijsenhout, the Netherlands. The first act of
asexual reproduction of 'Zanmumajes Red' was accom-
plished when after planting of the 'Zanmumajes Red' as a
motherplant in December 2013, vegetative cuttings from
this 'Zanmumajes Red' were taken and propagated further in
Rijsenhout, the Netherlands. In summer, about 6-8 days are
needed to initiate roots in cuttings of the new cultivar, after
another 5 days rooted plants are formed. The new cultivar

2

has been found to retain its distinctive characteristics
through successive propagations.

BRIEF DESCRIPTION OF THE DRAWINGS

5 The present invention of a new and distinct variety of
chrysanthemum (of about 19 weeks) is shown in the accom-
panying drawings, the color being as nearly true as possible
with color photographs of this type.

10 FIG. 1 shows a plant of the cultivar in full bloom.
FIG. 2 shows the various stages of blooms of the new
cultivar.
15 FIG. 3 shows the various stages of foliage of the new
cultivar.

DESCRIPTION OF THE INVENTION

20 The observations and measurements were gathered from
plants in the period of 16 to 23 weeks of age grown outdoor
in Rijsenhout, the Netherlands, under natural day length and
temperature and planted in week 23. The natural blooming
date of this crop was October 2 (week 40). The average
height of the plants was 35-40 cm. No growth retardants
25 were used. No tests were done on disease or insects resis-
tance or susceptibility. No tests were done on cold or
drought resistance. This new variety produces small sized
blooms with red-purple ray florets blooming for a period of
five weeks.

30 From the cultivars known to the inventor the most similar
existing cultivar in comparison to 'Zanmumajes Red' is
'Zanmumajes'. When 'Zanmumajes' and 'Zanmumajes
Red' are being compared the following differences are
noticed: (1) Color ray florets. And (2) Presence disc florets.
35 (1) Ray florets of 'Zanmumajes' are purple, while those of
'Zanmumajes Red' are more reddish purple. (2) Disc florets
are lacking in 'Zanmumajes' and some disc florets are
formed in 'Zanmumajes Red', especially when grown indoor.

The following is a description of the plant and characteristics that distinguish 'Zanmumajes Red' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour chart, sixth edition (2015).

TABLE 1

Botanical Description of <i>Chrysanthemum × morifolium</i> Ramat. 'Zanmumajes Red'		
<u>Bud</u>		
Size:	Small; cross-section 4 mm, height 3 mm	
Shape:	Round	
Texture:	Pubescent	
Outside color:	Greyed-green 191A	
Phyllaries		
Number:	21, arranged in 3 rows	
Shape:	Elliptic	
Apex:	Acute	
Base:	Truncate	
Margin:	Entire	
Color:	Upper side: Green 137C Lower side: Yellow-green 144C	
Length and width:	3 mm; 1.5 mm	
Texture:	Pubescent	
Inflorescences		
Type:	Double	
Height:	1 cm	
Diameter:	3 cm	
Peduncle length:	5.5-6.5 cm	
Peduncle color:	Green 143C	
Peduncle diameter:	1.5 mm	
Peduncle texture:	Pubescent	
Peduncle strength:	Weak	
Number per branch:	About 7-8 inflorescences	
Duration of flowering:	5 weeks	
Seeds:	Produced in small quantities, ovate, Greyed-brown 199A, length 1.5 mm, diameter 0.5 mm; texture: rough with ribs	
Fragrance:	Faint <i>chrysanthemum</i> odor	
Color inflorescences		
Center of inflorescence (disc florets):	Immature stage: Green-yellow 1D; Mature stage: Yellow 12A	
Color of upper side of ray florets:	Greyed-Purple 187B	
Color of lower side of ray florets:	Greyed-Purple 184B	
Tonality from distance:	A garden mum with small decorative dark red-purple blooms	
Color of ray florets after aging of the plant:	Greyed-Purple 183D	
Ray florets		
Number of types	One	
Type:	Ligulate	
Rows:	10-12	
Texture:	Upper and lower side smooth	
Number:	100-110	
Shape:	Elliptic	
Apex:	Pointed	
Base:	Attenuate	
Cross-section:	Flat	
Longitudinal axis:	Straight	
Length of corolla tube:	2 mm	
Diameter corolla tube:	0.8-1 mm	
Ray floret margin:	Entire	
Ray floret length:	1-1.5 cm	
Ray floret width:	2-4 mm	
Ratio length/width:	Medium	

TABLE 1-continued

Botanical Description of <i>Chrysanthemum × morifolium</i> Ramat. 'Zanmumajes Red'		
<u>5 Disc florets</u>		
Disc diameter:	1-2 mm	
Distribution of disc florets:	Small number in center of inflorescences	
Shape:	Tubular	
10 Color:	Yellow-green 145C at base to Green-yellow 1D at apex	
Length:	2 mm	
Diameter:	1 mm	
Receptacle		
<u>15 Color:</u>	Yellow-green 145D	
Shape:	Domed raised	
Height:	3 mm	
Diameter:	2.5 mm	
Reproductive Organs		
<u>20 Androecium:</u>	Present in only disc florets	
Stamen length:	2 mm	
Stamen color:	Yellow-green 144A	
Anther color:	Yellow 2A	
Pollen:	Low amount	
Pollen color:	Yellow 12A	
Gynoecium:	Present in ray and disc florets	
25 Style color:	Yellow-green 154C	
Style length:	3 mm	
Stigma color:	Yellow 7A	
Stigma width:	1 mm	
Ovary:	Enclosed in calyx; color: Yellow-green 149D	
<u>30 Plant</u>		
Type:	Bushy	
Growth habit:	Spherical shape	
Growth rate:	Medium	
Height:	35-40 cm	
Width:	50 cm	
35 Stem color:	Greyed-brown 199A	
Stem strength:	Weak	
Stem brittleness:	Brittle	
Stem anthocyanin coloration:	absent	
Internode length:	2 cm	
Length of lateral branch:	From top to bottom 20 cm	
40 Lateral branch color:	Green 138B	
Lateral branch, attachment:	Weak	
Lateral branch diameter:	2 mm	
Lateral branch texture:	Pubescent with ribs	
Branching (average number of lateral branches):	Dense with 9 breaks after pinching	
45 Natural season blooming date:	October 2 (week 40) in Rijshenhout, The Netherlands.	
Roots - habits:	Fine, freely branching	
Roots - color:	White 155D	
Foliation		
<u>50 Glossiness:</u>	Leaf upper side: very weak	
Leaf color:	Leaf lower side: very weak	
Color midvein:	Upper side: Green 138A	
55 Size:	GLower side:reen 139C	
Quantity (number per lateral branches):	Upper side: Yellow-green 147D	
Shape:	Lower side: Yellow-green 148D	
Texture upper side:	Small; length 3-4.5 cm, width 1.2-2.4 cm	
Texture under side:	20-22	
60 Venation arrangement:	Elliptic to widely elliptic	
Shape of margin:	Sparingly pubescent	
Shape of base of sinus between lateral lobes:	Pubescent	
Margin of sinus between lateral lobes:	Palmate	
65 Diverging	Serrated	
	Rounded

TABLE 1-continued

Botanical Description of <i>Chrysanthemum × morifolium</i> Ramat. 'Zanmumajes Red'	
Shape of base:	Attenuate
Apex:	Mucronulate
Petiole attitude:	Moderately upwards
Petiole length:	0.2-0.5 cm
Petiole diameter:	1.5 mm
Petiole color:	Yellow-green 147D
Stipules:	Very small, about 8 mm, at leaves at lower part of the branches

6

TABLE 2

Differences with the comparison variety, when grown under identical conditions		
	'Zanmumajes Red'	'Zanmumajes'
Ray floret upperside color	Greyed-purple 187B	Purple N77B
Presence disc florets	Few	Lacking

10

I claim:

1. A new and distinct *chrysanthemum* plant named 'Zanmumajes Red' as described and illustrated.
